COMBINED OPERATOR AND LATCH FOR A SWINGING WINDOW

Emory Glenn Simpson, Detroit, Mich., assignor to Ternstedt Manufacturing Company, Detroit, Mich., a corporation of Michigan

Application May 27, 1936, Serial No. 82,097

15 Claims. (Cl. 268—119)

This invention relates to a combined operator and latch for a swinging window.

It is the object of this invention to produce a combined operator and latch for a swinging window which is simple in structure, cheap to manufacture, and efficient in operation.

In the drawings:

Fig. 1 is a fragmentary side elevation of an automobile body showing the combined operator and lock used with the swinging glass of the no draft ventilating window.

Fig. 2 is a front elevation of the combined operator and latch showing the window closed and locked.

Fig. 3 is a section along the line 3—3 of Fig. 2. Fig. 4 is a section along the line 4—4 of Fig. 2. Fig. 5 is a section along the line 5—5 of Fig. 3. Fig. 6 is a detail of the latch bolt.

Fig. 7 is a view similar to Fig. 2 showing the latch bolt retracted.

Fig. 8 is a view similar to Fig. 2 showing a modified form of the invention with the swinging glass locked.

Fig. 9 is a view similar to Fig. 8 with the latch bolt retracted.

Fig. 10 is a section along the line 10—10 of Fig. 8.

Fig. 11 is a detail of the gear carried by the swinging glass support shaft.

Fig. 12 shows a second modified form of the invention.

Fig. 13 is a section along the line 13—13 of Fig. 12.

Fig. 14 is a third modified form of the invention.

Referring more particularly to the drawings there is shown a swinging glass panel 1 mounted in a channel section frame 4. The frame 4 is pivoted along its top edge as at 2 to a channel section weatherstrip frame 5 and supported at its lower edge by the shaft 3 so that it swings about a vertical axis. The frame 5 is fixed in the window opening.

The combined glass operator and lock is supported on a support plate 6 having a flange 7 which is welded to the base of the channel frame 5. A gear 8, having a socket extension 9 and a hub portion 10, is rotatably supported on the plate 6. The hub 10 of the gear 8 is journaled 45 in the support bearing 63 formed in the bottom wall of support plate 64 which is riveted to the plate 6 as at 65 (see Fig. 12). As shown in Fig. 5, a friction strap 11, welded as at 12 to the cover plate 13, is passed about the hub 10 and 50 drawn tight by the adjusting screw 14. Thus,

the strap 11 cooperates with the hub 10 to form a friction hinge support for the shaft 3 and frictionally hold the panel 1 against swinging otherwise permitted by the play in the window operating mechanism. The shaft 3 is set into the 5 socket 9 and held therein by the set screw 15.

A gear sector 16 is rotatably supported on the plate 6 by the pin 17. Another gear sector 18 is rotatably mounted on the plate 6 by a pin 19. The gear sector 18 meshes with the driving pinion 20 fixed on the spindle 21 which carries the usual operating crank handle 22. A pair of toggle levers 23 and 24 are pivotally connected by the pin 25. The lever 23 is pivotally connected to the sector 16 by the pin 26. The lever 24 is pivotally connected to an adjustable support plate 27 by the pin 28 (Fig. 4). The adjustable support plate 27 is carried by support plate 29 which is riveted to the support plate 6 by rivets 30. The rivets 30 pass through the elongated 20 slots 31 in the plate 27 and have enlarged heads whereby the plate 27 is slidably retained upon the plate 29. The plates 27 and 29, shown in Fig. 4, have flanges 32 and 33. An adjusting screw 34 is threaded into the tapped opening 35 25 in the flange 32 and is journaled into the flange 33 as at 36 and into a flange 37 on the support plate 6 as at 38. The screw 34 is provided with a square head 39 by means of which it can be turned to adjust the plate 27 along the plate 29. 30 The plate 27 is adjusted upon its support 29 so that the toggle levers 23 and 24 are at, or slightly over, center when the window glass is completely closed. A draft link 40 is also pivotally connected to the toggle at the elbow by the pin 35 25 25 and is pivotally connected to the gear sector 18 by the pin 41 which is riveted to the sector 18 as at 42.

The cover plate 13 which is riveted to the support plate 6, as at 45, serves as a support and 40 guide for the bolt 46. The cover plate 13 has an opening 47 through which the bolt passes and a pin 48 pivoted thereto which engages the bolt in the elongated slot 49. The bolt also passes through an opening 50 in the flange 7 of the support plate 6 and the base of the weatherstrip channel 5. The weatherstrip 51 is also provided with an opening 52 through which the bolt is projected into engagement with a keeper opening 53 in the base of the window glass frame 4. 50

For projecting and retracting the bolt 46 the lower end of the bolt is provided with a slot 54. The slot 54 is positioned so that it will interengage the pin 41 on the sector 18 as the swinging glass 1 reaches closed position and during 55

closed position and the initial movement of the operator in the opening of the swinging glass.

The operation of this device is as follows: As shown in Fig. 2, the window panel 1 is closed.

- 5 The bolt 46 is interengaged with the opening 53 in the glass frame 4 thus locking the swinging window in closed position. At this time the toggles 24 are either at, or slightly above, center, that is, a line passing through pins 26 and 28. To 10 open the window, as viewed in Fig. 2, the crank 22 and pinion 20 are turned counterclockwise which causes sector 18 to rotate clockwise about its support 19 and through draft link 48 break the toggle downwardly and rotate the sector 16 clockwise which in turn through gear 8 and the shaft 3 swings the window to open position. As the sector 18 swings clockwise to break the toggle downwardly, the pin 41 engages the bottom edge 57 of the slot 54 thus camming or retracting the bolt 46 from the keeper opening 53 before the 15 window panel 1 begins to swing open. After the toggle is broken downwardly past center, the gears 16 and 8 begin to turn, as above described, to open the window.
- 20 When the window is closed and the bolt 46 projected, it will be noted that the pin 41 is seated against the inner end of the slot 54 and that the pin 48 engages the bottom of the elongated slot 49. As the gear 18 continues to turn in the 25 opening of the window, the pin 41 rides out of the slot 54 just as the pin 48 abuts the upper end of the slot 49, as indicated in the dotted line showing, Fig. 7. Thus, the pin 48 holds the bolt in the proper position so that upon closing the panel 1 30 the pin 41 will again enter slot 54.

In closing the window the crank 22 is turned so that the gear 18 rotates counterclockwise which, acting through the link 40, moves the toggle lever center upwardly to enlarge the overall 40 length of the toggle and rotate the gear 16 counterclockwise which, through the gear 8 and shaft 3, closes the window. As the toggle approaches center position, pin 41 engages the upper edge 58 of notch 54 thereby camming the bolt 46 upwardly into engagement with the keeper 53. The rotation of the gear 18 continues until the toggle is moved to center, or slightly over, center position. In other words, the swinging panel operating mechanism opens and closes the window 45 glass 1 and after the window reaches closed position, or before the window glass starts to open, the toggle elbow can be moved slightly below center without materially shortening the overall length of the toggle or causing any material 50 movement of the gear 16. Similarly in closing the panel 1, the panel 1 reaches closed position just before the toggle reaches center and further movement of the toggle to center causes no appreciable movement of pin 26 away from pin 28. 55 This lost motion of the toggle at or near center position is utilized to either project or retract the bolt 46 while the window is closed.

In Figs. 8, 9 and 10, there is shown a modified form of the invention. In this arrangement the 60 swinging window 1 and gear 8 are mounted the same as in the principal form of the invention and the pinion 20 drives the gear 18 which is rotatably mounted on the shaft 19. The gear 8 has fixed thereto the lever 60 which rotates with 65 the gear 18 about the shaft 19. The sector 16 is rotatably mounted on the shaft 17 and meshes with the gear 8. In this form of the invention the toggle levers 23 and 24 are mounted as above described but are positioned below, instead of 70 above, the shaft 17. A draft link 40 is pivotally

connected to the lever 60 by the pin 61. The bolt 46 is mounted the same as above described but is projected and retracted by a pin 62 carried on the toggle lever 24.

In this form of the invention when the pinion 20 is turned counterclockwise the gear 18 rotates clockwise thus breaking the toggle 23, 24 downwardly and which causes the sector 16 to rotate counterclockwise which, acting through gear 8 and shaft 3, swings the window open. In this 5 form of the invention the pin 62 cooperates with the slot 54 and the bolt 46 the same as pin 41 in the principal form of the invention. Thus, when the window glass is closed the initial turning movement of the pinion 20 causes the toggle 10 23, 24 to break downwardly from its position slightly above or at center thus causing the pin 62 to cam the bolt 46 downwardly and out of engagement with the keeper 53 before the window 15 glass begins to swing open.

In the closing of the window, as illustrated in Fig. 9, as the toggle 23 nearly reaches straightened position the window glass is closed. Further movement of the toggle toward the straight position causes the pin 62 to engage the slot 54 and project the bolt 46 into engagement with the keeper 53 in the window glass frame.

A second modified form of the invention is shown in Figs. 12 and 13. In this form of the invention the gear 8 is mounted the same as previously described. The gear sector 16, which meshes with the gear 8, is freely rotatably mounted upon the spindle 21 on which driving pinion 20 is fixed. Thus, the shaft 21 is free to turn independently of the sector 16 but the 30 pinion 20 always turns with the shaft 21. The pinion 20 meshes with the gear sector 66 which is pivotally mounted on the pin 67. The toggle levers 23 and 24 are the same as in the principal 35 form of the invention and the draft link 40 is pivotally mounted to the gear sector 66 by the pin 68.

In this form of the invention when the pinion 20 rotates in the direction of the arrow, the gear 66 turns clockwise about the shaft 67, thus drawing the link 40 downwardly and breaking the toggle downwardly. Thus, the toggle, through pin 26, rotates the sector 16 clockwise in the direction of the arrow and causes the window to open. In closing the window the reverse of this 50 operation takes place.

When the window is closed the bolt 46 interengages the keeper opening 53 in the window glass channel 4, and the toggles 23 and 24 are at, or slightly above, center position. The initial turning movement of the gear 66 to break the toggle downwardly does not materially rotate the gear 16. This initial movement of the gear 66 is translated to the bolt 46 to retract the same by the lever 69 carried by the gear 66 which engages a notch 70 in the bolt 46. In the downward or clockwise rotation of the lever 69, it engages the bottom face 71 of the notch 70 and cams the bolt 46 downwardly as indicated by the dotted line showing. In closing after the window glass 1 reaches closed position, the lever 69 engages the upper face 72 of the notch 70 and draws the bolt 46 upwardly into interengagement with the keeper 53 of the glass frame 4. The upward movement of the lever 69 is arrested by the stop pin 73.

In Fig. 14 there is shown a third modified form of the invention which is similar in all respects to the principal form of the invention except that in the principal form of the invention the pin 41 serves a double purpose; namely, it pivotally con- 75

ncts the link 40 to the sector 18 and also cooperates with the slot 54 to project and retract the bolt whereas in this modified form a pin 75 pivotally connects the link 40 with the sector 18 and a separate pin 76, mounted on a projection 77 of the gear 18, cooperates with the notch 54 to project and retract the bolt 46.

The operation of this modified form is the same as that of the principal form.

10 I claim:

1. In a window assembly having a window panel adapted for movement to open and closed positions, mechanism for moving the window to open and closed positions including a toggle, a locking mechanism interengageable with the said window panel when closed for locking the same, and a separable connection connected to said toggle between the ends of the same and also connected to the locking mechanism for operatively connecting the locking mechanism and the toggle only when the window panel is closed and during the initial breaking and final straightening movements of the said toggle whereby the said window panel is locked after reaching closed position and unlocked before opening.

2. In a window assembly having a window panel adapted for movement to open and closed positions, mechanism for moving the window panel to open and closed positions including a toggle the elbow of which approaches center position in the closing of the window panel, a locking mechanism interengageable with the said window panel when closed for locking the same, and a disconnectable operative connection connected to said toggle between the ends of the same and also connected to said locking mechanism, the said operative connection being disconnected when the window panel is open and ineffective to interengage the locking mechanism and the window panel and being connected and effective to interengage the locking mechanism and the window panel after the panel is closed and as the toggle approaches center.

3. In a window assembly having a window panel adapted for movement to open and closed positions, mechanism for moving the window panel to open and closed positions including a toggle the elbow of which approaches center position in the closing of the window panel, a latch bolt, a keeper for the said bolt carried by the window panel, the said bolt being projectable into interengagement with the said keeper to lock the window when closed, and a disconnectable operative connection between the latch bolt and the said toggle, the said connection being connected to said toggle approximately at the elbow of the same, the said operative connection being disconnected from the bolt when the window panel is open and connected and effective to project the bolt into interengagement with the window panel when the panel is closed and as the toggle approaches center.

4. In a window assembly having a window panel adapted for movement to open and closed positions, mechanism for moving the window panel to open and closed positions including a toggle the elbow of which approaches center position when the mechanism is operated to close the window panel, a latch bolt and a keeper therefor carried by the window panel, a separable connection between the latch bolt and the toggle, said connection being connected to said toggle intermediate the ends of the same, the said separable connection operatively connecting the latch bolt to the toggle as the toggle approaches

center position in the closing of the window to project the latch bolt into interengagement with the keeper after the window reaches closed position, the said connection retracting the latch bolt from the keeper before the window panel starts to move to open position as the toggle leaves center position when the mechanism is operated to open the window and the connection subsequently separating to disconnect the latch bolt and the toggle.

5. In a window assembly having a window panel adapted for movement to open and closed positions, mechanism for moving the window panel to open and closed positions including a toggle the elbow of which approaches center position when the mechanism is operated to close the window panel, a latch bolt retractable through a predetermined range, a keeper therefor carried by the window panel, a separable connection between the latch bolt and the toggle, said connection being connected to said toggle intermediate the ends of the same, the said separable connection operably connecting the latch bolt to the toggle as the toggle approaches center position in the closing of the window panel to project the latch bolt into interengagement with the keeper after the window reaches closed position, the said connection retracting the latch bolt from the keeper as the toggle leaves center position before the window panel starts to move to open position and through a predetermined range when the mechanism is operated to open the window panel and the connection separating as the latch bolt reaches the end of its range of movement to disconnect the latch bolt from the toggle.

6. In a window assembly having a window panel adapted for movement to open and closed positions, mechanism for moving the window panel to open and closed positions including a toggle the elbow of which approaches center position when the mechanism is operated to close the window panel, a reciprocable latch bolt, stop means permitting reciprocation of the bolt through a predetermined range, a keeper therefor carried by the window panel, a separable connection between the latch bolt and the elbow of said toggle, the said separable connection operably connecting the latch bolt to the toggle as the toggle approaches center position in the closing of the window panel to project the latch bolt into interengagement with the keeper after the window reaches closed position, the said connection retracting the latch bolt from the keeper as the toggle elbow leaves center position before the window panel starts to move to open position and through a predetermined range when the toggle is operated to open the window and the connection separating as the latch bolt reaches the end of its range of movement to disconnect the latch bolt from the toggle.

7. In a window assembly having a swinging window panel adapted for swinging to open and closed positions, mechanism for swinging the window panel to open and closed positions including a toggle the elbow of which approaches center position when the mechanism is operated to close the swinging window panel, a reciprocable latch bolt, stop means permitting reciprocation of the bolt through a predetermined range in a direction across the straightened toggle, a keeper therefor carried by the swinging window panel, a separable connection between the latch bolt and the toggle elbow, the said separable connection operably connecting the latch bolt to

- the toggle as the toggle elbow approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open position and through a predetermined range when the mechanism is operated to open the swinging window and the connection separating as the latch bolt reaches the end of its range of movement to disconnect the latch bolt from the toggle.
8. In a window assembly having a swinging window panel adapted for swinging to open and closed positions, mechanism for swinging the window panel to open and closed positions including driving and driven gears and a toggle for transmitting the driving torque from one gear to the other, the said toggle elbow approaching center position when the mechanism is operated to close the swinging window panel, a reciprocable latch bolt, stop means permitting reciprocation of the bolt through a predetermined range, a keeper therefor carried by the swinging window panel, a separable connection between the latch bolt and the mechanism for swinging the said window panel, the said separable connection operably connecting the latch bolt to the mechanism for swinging the window panel as the toggle elbow approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open position and through a predetermined range when the mechanism is operated to open the swinging window and the connection separating as the latch bolt reaches the end of its range of movement to disconnect the latch bolt from the mechanism for swinging the window.
9. In a window assembly having a swinging window panel adapted for swinging to open and closed positions, a support, mechanism for swinging the window panel to open and closed positions mounted on said support, the said mechanism including driven and driving gears and a toggle, one end of which is pivotally secured to the support and the other end of which is pivotally connected to the driven gear, means operatively connecting the toggle to the driving gears, the said toggle elbow approaching center position when the mechanism is operated to close the swinging window panel, a reciprocable latch bolt, stop means permitting reciprocation of the bolt through a predetermined range, a keeper therefor carried by the swinging window panel, a separable connection between the latch bolt and the mechanism for swinging the said window panel, the said separable connection operably connecting the latch bolt to the mechanism for swinging the window panel as the toggle elbow approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open position and through a predetermined range when the mechanism is operated to open the swinging window and the connection separating as the latch bolt reaches the end of its range of movement to disconnect the latch bolt from the mechanism for swinging the window.

the swinging window and the connection separating as the latch bolt reaches the end of its range of movement to disconnect the latch bolt from the mechanism for swinging the window.

10. In a window assembly having a swinging window panel adapted for swinging to open and closed positions, a support, mechanism for swinging the window panel to open and closed positions mounted on said support, the said mechanism including driving and driven gears and a toggle one end of which is pivotally secured to the support and the other end of which is pivotally connected to the driven gear, a link one end of which is pivotally connected to the toggle and the other end of which is pivotally connected to the driving gear whereby when the driving gear is rotated the toggle is broken toward the said driving gear which causes the driven gear to rotate, the said toggle elbow approaching center position when the mechanism is operated to close the swinging window panel, a reciprocable latch bolt, stop means permitting reciprocation of the bolt through a predetermined range, a keeper therefor carried by the swinging window panel, a separable connection between the latch bolt and the mechanism for swinging the said window panel, the said separable connection operatively connecting the latch bolt to the mechanism for swinging the window panel as the toggle elbow approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open position and through a predetermined range when the mechanism is operated to open the swinging window and the connection separating as the latch bolt reaches the end of its range of movement to disconnect the latch bolt from the mechanism for swinging the window.
11. In a window assembly having a swinging window panel adapted for swinging to open and closed positions, a support, mechanism for swinging the window panel to open and closed positions mounted on said support, the said mechanism including driving and driven gears and a toggle one end of which is pivotally secured to the support and the other end of which is pivotally connected to the driven gear, a link one end of which is pivotally connected to the toggle and the other end of which is pivotally connected to the driving gear whereby when the driving gear is rotated the toggle is broken toward the said driving gear which causes the driven gear to rotate, a driving pinion for turning the driving gear and a gear fixed to the swinging window support shaft and meshed with the driven gear for swinging the said window panel, the said toggle elbow approaching center position when the mechanism is operated to close the swinging window panel, a reciprocable latch bolt, stop means permitting reciprocation of the bolt through a predetermined range, a keeper therefor carried by the swinging window panel, a separable connection between the latch bolt and the mechanism for swinging the said window panel, the said separable connection operatively connecting the latch bolt to the mechanism for swinging the window panel as the toggle elbow approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open position and through a predetermined range when the mechanism is operated to open the swinging window and the connection separating as the latch bolt reaches the end of its range of movement to disconnect the latch bolt from the mechanism for swinging the window.

window panel reaches closed position, the said connection retracting the latch bolt from the keeper as the toggle elbow leaves center position before the swinging window panel starts to move 5 to open position and through a predetermined range when the mechanism is operated to open the swinging window and the connection separating as the latch bolt reaches the end of its range of movement to disconnect the latch bolt from 10 the mechanism for swinging the window.

12. In a window assembly having a swinging window panel adapted for swinging to open and closed positions, mechanism for swinging the window panel to open and closed positions including a driven gear and a driving mechanism for the driven gear comprising a driving gear, a toggle one end of which is pivotally connected to the driven gear and the other end of which has a fixed pivot, the said toggle being operatively 20 connected with the driving gear so that the toggle is approximately on center when the window panel is closed, a reciprocable latch bolt, stop means permitting reciprocation of the bolt through a predetermined range, a keeper for the 25 bolt carried by the swinging window panel, a pin and a slot connection between the latch bolt and the said driving mechanism, the said pin and slot connection operatively connecting the latch bolt to the mechanism for swinging the window panel 30 as the toggle approaches center position in the closing of the swinging window panel to project the latch bolt into interengagement with the keeper after the window panel reaches closed position, the said pin and slot connection retracting 35 the latch bolt from the keeper as the toggle elbow leaves center position before the swinging window panel starts to move to open position and through the said predetermined range when the mechanism is operated to swing the swinging 40 window, and the pin separating from the slot as the latch bolt reaches the end of its range of movement to disconnect the latch bolt from the driving mechanism for the said driven gear.

13. In a window assembly having a swinging window panel adapted for swinging to open and closed positions, mechanism for swinging the window panel to open and closed positions including a driven gear and a driving mechanism for the driven gear comprising a driving gear, a 45 toggle one end of which is pivotally connected to the driven gear and the other end of which has a fixed pivot, the said toggle being operatively connected with the driving gear so that the toggle is approximately on center when the window panel is closed, a reciprocable latch bolt, stop means permitting reciprocation of the bolt through a predetermined range, a keeper for the 50 bolt carried by the swinging window panel, a pin carried by the driving gear and a slot in the said bolt, the said pin and slot connected operatively 55 connecting the latch bolt to the mechanism for swinging the window panel as the toggle approaches center position in the closing of the swinging window panel to project the latch bolt into interengagement with the keeper after the window panel reaches closed position, the said pin and slot connection retracting the latch bolt from the keeper as the toggle elbow leaves center position before the 60 swinging window panel starts to move to open 65 position and through the said predetermined range when the mechanism is operated to swing the swinging window, and the pin separating from the slot as the latch bolt reaches the end of its range of movement to disconnect the 70 latch bolt from the driving mechanism for the said driven gear.

the latch bolt from the driving mechanism for the said driven gear.

14. In a window assembly having a swinging window panel adapted for swinging to open and closed positions, mechanism for swinging the window panel to open and closed positions including a driven gear and a driving mechanism for the driven gear comprising a driving gear, a toggle one end of which is pivotally connected to the driven gear and the other end of which has a fixed pivot, the said toggle being operatively connected with the driving gear so that the toggle is approximately on center when the window panel is closed, a reciprocable latch bolt, stop means permitting reciprocation of the bolt through a predetermined range, a keeper for the bolt carried by the swinging window panel, a pin carried by one of the toggle levers and a slot in the said bolt, the said pin and slot connection operatively connecting the latch bolt to the mechanism for swinging the window panel as the toggle approaches center position in the closing of the swinging window panel to project the latch bolt into interengagement with the keeper after the window panel reaches closed position, the said pin and slot connection retracting the latch bolt from the keeper as the toggle elbow leaves center position before the swinging window panel starts to move to open position and through the said predetermined range when the mechanism is operated to swing the swinging window, and the pin separating from the slot as the latch bolt reaches the end of its range of movement to disconnect the latch bolt from the driving mechanism for the said driven gear.

15. In a window assembly having a swinging window panel adapted for swinging to open and closed positions, mechanism for swinging the window panel to open and closed positions including a driven gear and a driving mechanism for the driven gear comprising a driving gear, a toggle one end of which is pivotally connected to the driven gear and the other end of which has a fixed pivot, the said toggle being operatively connected with the driving gear so that the toggle is approximately on center when the window panel is closed, a reciprocable latch bolt, stop means permitting reciprocation of the bolt through a predetermined range, a keeper for the bolt carried by the swinging window panel, a driving connection between the driving gear and the said bolt comprising a projection carried by the said driving gear and a slot in the said bolt adapted for engagement with the said projection, the said connection operatively connecting the latch bolt to the mechanism for swinging the window panel as the toggle approaches center position in the closing of the swinging window panel to project the latch bolt into interengagement with the keeper after the window panel reaches closed position, the said connection retracting the latch bolt from the keeper as the toggle elbow leaves center position before the swinging window panel starts to move to open 60 position and through the said predetermined range when the mechanism is operated to swing the swinging window, and the projection separating from the slot as the latch bolt reaches the end of its range of movement to disconnect the latch bolt from the driving mechanism for the said driven gear.
